UNITED STATES PATENT OFFICE.

FLETCHER D. HALLOCK, OF WILKINSBURG, PENNSYLVANIA, ASSIGNOR TO T. H. GIVEN, H. S. A. STEWART, AND E. M. HERR, OF PITTSBURG, PENNSYLVANIA, RECEIVERS OF WESTINGHOUSE ELECTRIC & MANUFACTURING COMPANY, OF EAST PITTSBURG, PENNSYLVANIA, A CORPORATION OF PENNSYLVANIA.

MOTOR-CONTROLLING DEVICE.

No. 895,012.

Specification of Letters Patent.

Patented Aug. 4, 1908.

Application filed November 8, 1907. Serial No. 401,311.

To all whom it may concern:

Be it known that I, FLETCHER D. HALLOCK, a citizen of the United States, and a resident of Wilkinsburg, in the county of Allegheny and State of Pennsylvania, have invented a new and useful Improvement in Motor-Controlling Devices, of which the following is a specification.

My invention relates to starting and speed regulating devices for electric motors, and it has for its object to provide simple and effective means that may be employed in connection with any of the well known standard forms of starting rheostats for insuring substantially maximum field strength of the motor when starting the same.

Figure 1, of the accompanying drawings, is a face view of a starting rheostat embodying my invention, the circuit connections being also illustrated therein. Fig. 2 is an enlarged detail view of one of the parts of the device shown in Fig. 1, and Fig. 3 is a diagrammatic view illustrating a modification of the invention.

25 In Fig. 1, a starting rheostat 1, in connection with which the invention is employed, is one of the standard and well known forms, and comprises a pivoted switch arm 2, a series of stationary contact terminals 3 with 30 which the arm 2 engages, and a resistance member 4 suitable points of sub-division of which are connected to said contact terminals, the said resistance member being included in series with the armature 5 of an 35 electric motor 6 and serving as a starting resistance therefor.

The switch arm 2 is provided with a removable lug or button 7, in the path of movement of which is interposed a bow-spring 8 40 that is attached to an insulating supporting piece 9, which, in turn, is carried by a pivoted armature 10 for an electro-magnet 11 having an energizing winding 12, the armature 10 being normally maintained in the position shown by means of a spring 13. One terminal of the magnet winding 12 is connected to a switch member 14 that is carried by the armature 10 and is adapted to engage a stationary switch member 15 to which 45 a terminal 16 of the rheostat is connected. The other terminal of the magnet winding 12 is connected to terminal 17 of the rheostat 50

which, in turn, is connected to one terminal 18 of a rheostat 19 that is included in series circuit with shunt field magnet winding 20 of 55 the motor 6, one terminal of the said winding being also connected to terminal 16 of the starting rheostat.

Terminals 21 and 22 of the starting rheostat 1 are connected, as usual, to circuit conductors 23 and 24 of a suitable supply circuit, and a terminal 25 is connected, as usual, to a terminal of the armature 5 of the motor 6, the other terminal of the motor being connected to circuit conductor 24.

It will be observed that the magnet winding 12 and the switch comprising members 14 and 15 are included in a circuit in shunt to the field rheostat 19, this circuit being established when the switch arm 2 is moved from 70 left to right in order to effect starting of the motor by removing the resistance 4 from the armature circuit thereof, the lug 7 thereupon engaging the spring 8 and forcing the switch member 14 into engagement with the member 15.

If switch arm 26 of the field rheostat 19 occupies the position shown in full lines, when the circuit in shunt to the field rheostat is established, a comparatively small 80 amount of current will traverse the magnet winding 12, and an insufficient degree of attraction will therefore be exerted by the magnet core 11 to maintain the armature 10 in its attracted position and the switch members 14 and 15 in engagement after the lug 7 upon the switch arm 2 has moved out of engagement with the spring 8. The switch members 14 and 15 will, therefore, be separated, and regulation of the amount 90 of resistance in the circuit of the shunt field magnet winding 20 may be effected in the usual manner by moving the rheostat arm 26 in a clockwise direction. If, however, the position of the rheostat arm 26 is such that the resistance of the magnet winding 12 is materially less than that included in circuit with the shunt field magnet winding 20, as, for example, that indicated by broken lines, a relatively large 100 amount of current will traverse the magnet winding 12, and the armature 10 will, therefore, be maintained in its attracted position by the magnet 11 after the lug 7

becomes disengaged from the spring 8, whereby the switch members 14 and 15 will be maintained in engagement. The field rheostat 19 is thereby shunted, and adjustment of the field strength of the motor cannot then be effected by further movement of the rheostat arm 26 in a clockwise direction, unless and until the said arm is first returned in a counter-clockwise direction to a position such that the resistance of the magnet winding 12 may not be greatly in excess of the resistance introduced in the shunt field circuit by the rheostat 19. Under such conditions, the spring 13 will overcome the force of attraction exerted by the magnet 11 upon the armature 10, and the switch members 14 and 15 will thereupon become disengaged. Adjustment of the amount of resistance in the shunt field circuit may then be effected as usual, by movement of the rheostat arm 26 in a clockwise direction.

In Fig. 1, the switch governing the shunt to the field resistance is operated directly by movement of the switch arm 2, but in the arrangement shown diagrammatically in Fig. 3, it is necessary to manually close a switch 28 by means of a handle 29 in order that a hook 30 carried by the movable member of the switch 28 may be disengaged from a post 31 carried by a switch arm 32 and thereby permit movement of the said switch arm from left to right for the purpose of removing resistance from the armature circuit. It will be understood that the switch 28 will remain closed so long as the resistance introduced in the circuit by the field rheostat 33 materially exceeds the resistance of the retaining magnet winding 34 for the said switch 28 and that the operation of the system of Fig. 3 is otherwise substantially like that of Fig. 1.

It will be understood that structural details may be varied otherwise than as specifically indicated without departing from my invention.

I claim as my invention:

1. The combination with an electric motor, a resistance in the armature circuit thereof, and means for removing the said resistance from circuit, of a resistance for the field circuit of the motor, and means for establishing a circuit in shunt to said field resistance upon removal of resistance from the armature circuit, and for maintaining the said shunt circuit while the field resistance exceeds a predetermined value.

2. The combination with an electric motor, a resistance in the armature circuit thereof, and a switch arm for removing the said resistance from circuit, a resistance for the field circuit of the motor, a switch operated by the said switch arm to establish a circuit in shunt to the field resistance, and an electro-magnet, winding in the shunt circuit for maintaining

the switch in closed position while the field resistance exceeds a predetermined value.

3. The combination with an electric motor, a resistance in the armature circuit thereof, and a switch arm for removing the said resistance from circuit, a resistance for the field circuit of the motor, a switch operated by the said switch arm to establish a circuit in shunt to the field resistance, and an electro-magnet winding in the shunt circuit for maintaining the switch in closed position while the field resistance exceeds that of the shunt circuit by a predetermined amount.

4. The combination with an electric motor, a resistance in the armature circuit thereof, and means for removing said resistance from circuit, of a resistance for the field circuit of the motor, a switch for establishing a circuit in shunt to the field resistance upon removal of resistance from the armature circuit, and means for maintaining the switch in closed position while the field resistance exceeds a predetermined value.

5. The combination with an electric motor, a resistance in the armature circuit thereof, and means for removing said resistance from circuit, of a resistance for the field circuit of the motor, a switch for establishing a circuit in shunt to the field resistance upon the removal of resistance from the armature circuit, and an electro-magnet in the shunt circuit for maintaining the switch in closed position while the field resistance exceeds a predetermined value.

6. The combination with an electric motor, a resistance in the armature circuit thereof, and a switch arm for removing the said resistance from circuit, of a resistance for the field circuit of the motor, a switch for establishing a circuit in shunt to the field resistance, means for preventing movement of the switch arm to remove resistance from the armature circuit except by first closing the said switch, and means for maintaining the switch in closed position while the field resistance exceeds a predetermined value.

7. The combination with an electric motor, a resistance in the armature circuit thereof, and means for removing the said resistance from the circuit, of a resistance for the field circuit of the motor, means for preventing removal of resistance from the armature circuit except by first establishing a circuit in shunt to the field resistance, and means for maintaining the shunt to the field resistance while the said resistance exceeds a predetermined value.

In testimony whereof, I have hereunto subscribed my name this 31st day of Oct., 1907.

FLETCHER D. HALLOCK.
